Filed July 15, 1958, Ser. No. 748,721

7 Claims. (Cl. 1—177)

This invention relates to feeding mechanisms for feeding material to presses and the like. The invention is disclosed herein with conjunction with a crimping press for electrical terminals in strip form, however, it will be obvious that the invention is adaptable to other uses.

An object of the present invention is to provide an improved feeding mechanism for a crimping press or the like. A more specific object is the provision of a feeding mechanism capable of positioning precisely and accurately an electrical terminal with relation to a set of crimping dies. Such precise and accurate positioning of the terminal is important in the connector art by reason of the fact that the crimping of connectors onto wires is an exacting operation and the terminal must be precisely positioned with respect to the crimping dies if a proper crimped connection is to be obtained.

A further object of the invention is to provide a terminal feeding means which is readily adjustable both with respect to the length of the feeding stroke and with respect to the position of the fed terminal at the end of the feeding stroke. This object is of importance for the reason that electrical connectors and terminals are provided and used in a wide variety of sizes and shapes, and if a crimping press is to be used for several of the various types of connectors available, it should be capable of being adjusted rapidly and accurately to accommodate the different lengths of feed strokes required.

A further object is to provide a terminal feeding mechanism in which the parts such as the feed finger are of relatively light weight and in which the feeding takes place in steady, even and in a relatively gentle manner. It is important in the connector art that feeding be accomplished in this manner for the reason that many connectors are relatively small and may be produced from sheet metal which is relatively thin, for example, 0.016 inch in thickness. The feeding of connectors of such thin sheet metal should be relatively gentle and should not impose undue stresses on the connectors since they can easily be bent or otherwise deformed during the feeding step.

A further object of the invention is to provide a feeding mechanism which has a uniform acceleration and deceleration feed stroke and in which the stroke and the final position of the fed terminal can be changed without disturbing the uniform acceleration and deceleration motion.

A further object is to provide a feeding mechanism in which the length of the feed stroke can be changed without changing the position of feed finger at the end of the stroke.

Other objects and attainments of the present invention will become apparent to those skilled in the art upon a reading of the following detailed description when taken in conjunction with the drawings in which there is shown and described an illustrative embodiment of the invention; it is to be understood, however, that this embodiment is not intended to be exhaustive nor limiting of the invention but is given for purposes of illustration in order

2

that others skilled in the art may fully understand the invention and the principles thereof and the manner of applying it in practical use so that they may modify it in various forms, each as may be best suited to the conditions of a particular use.

In the drawings:

Figure 1 is a frontal view of a crimping press incorporating a feeding mechanism in accordance with the invention;

10 Figure 2 is a view taken along the lines 2—2 of Figure 1;

Figure 3 is a view taken along the lines 3—3 of Figure 1;

15 Figure 4 is a frontal view showing the feeding mechanism on an enlarged scale;

Figure 5 is a view taken along the lines 5—5 of Figure 4; and

Figure 6 is a view taken along the lines 6—6 of Figure 4.

20 The disclosed embodiment of the invention is shown in conjunction with a crimping press comprising a generally V-shaped frame 2 secured to a surface by means of gibs 4 and having a power shaft 6 journaled for rotation in its upper portion 8. On one end of shaft 6 a sprocket 10 is provided which is coupled by means of a chain 12, which passes over an idler sprocket 14, to a suitable source of power such as an electric motor (not shown). The particular embodiment shown is thus adapted for continuous operation as in a fully automatic lead making machine, for example, of the type shown in the copending application of Glendon Schwalm et al., Serial Number 748,722 filed July 15, 1958 for Lead Making Machine and Method (122,963). However, the invention is adaptable for use in the commonly known semiautomatic crimping presses in which a foot switch is provided and the operator manually positions the wire to which the terminal is to be crimped. In the latter type of press, a suitable clutch may be provided to cause the ram to descend under the control of the operator.

25 40 Shaft 6 has an eccentric 16 keyed or otherwise secured to its opposite end which eccentric is contained between plates 18. An eccentric strap or hub 20 surrounds eccentric 16 and has an extension 22 extending therefrom. A pin 24, adjustably secured to extension 22, has a ball and socket pivotal connection 26 with a press ram 28 mounted for reciprocation between gibs 30 secured to the sides of the frame. On its lower end this ram carries crimping tooling including, in the disclosed embodiment, a slugout blade 32 for removing the short slugs of metal which connect adjacent strip terminals, a wire barrel crimper 34 which crimps a portion of the terminal onto the stripped end of the wire and an insulation barrel crimper 36 which crimps an insulation barrel of the connector onto the insulation of the conductor. Advantageously, a knock-out bar 37 is provided for the purpose of dislodging the crimped terminal from the crimping dies 34, 36. This bar is fixed with relation to the crimping dies so that as the ram ascends, if a crimped terminal is lodged in the crimpers, it will engage the stationary knock-out device and be dislodged. A pedestal 38 extends from the base of press frame 2 and has mounted on its upper surface a plate 41. The lower crimping dies or anvils 40 are secured to a block 42 which is supported and adjustably secured to this plate. These dies are not specifically identified or described since their construction is commonly known to the art and will vary, in any event, with the specific type of terminal being crimped. It will be noted from Figure 1 that the crimping dies 40 and anvils are mounted in such manner that the wire is adapted to be fed from the left in this figure and the terminal fed from the right. The invention is not limited

to this arrangement but is adaptable to the common alternative arrangement of inserting the wire from the front toward the press and feeding the terminals from the rear toward the front of the press.

The terminals T (Figure 4) are fed from a suitable source such as a reel or spool over block 42 which is adjustably secured by means of machine screws 44 extending through slots 46 in the block and into threaded openings in the plate 41. Thus the block can be adjusted leftwardly or rightwardly as viewed in Figure 4 to permit accurate positioning of the lower tooling with respect to the upper tooling. An adjusting screw 48 is threadedly received within the end of block 42 and has a circumferential recess which receives a pin 50 extending from plate 41 so that as screw 48 is rotated, the block is moved leftwardly or rightwardly depending upon the direction of rotation. For more accurate guiding of this block, an additional pin 52 is provided near the opposite end of the block which is received within a slot 54.

The upper surface of the block 42 has mounted thereon a pair of parallel plates 56 by means of machine screws 58 which plates define a terminal feed path for the terminals entering the feed mechanism. A bracket 62 extends from block 42 along one side thereof and an additional block 60 is secured to this bracket. Block 60 extends substantially parallel to and above the feed track defined by plates 56 and has an internal bore 63 in which is reciprocably mounted a feed plunger 64. An ear 66 extends from the underside of plunger 64 through a slot in block 60 and has pivotally mounted on its end a feed finger 68 which is normally biased in a counterclockwise direction, as viewed in Figure 4, by means of a light spring 70. The biasing force of spring 70 should be such that the feed finger is permitted to rotate clockwise as viewed in Figure 4 during the return stroke of the plunger in order to permit it to ride over the first terminal in the strip being fed.

An additional ear 72 extends from the opposite side of plunger 64 through a slot in bore 63. Block 60 is cut away as indicated at 71 and an additional bore 76 is provided which is parallel to bore 63. A spring 74 in bore 76 is secured at its front and to ear 72 and is anchored to block 60 at its rearward end as viewed in Figure 4 so that this spring normally biases plunger 64 to the right as viewed in that figure.

A terminal feed slide member 78 is also received within bore 63 and has a set screw 80 extending from one end thereof which set screw abuts the end of plunger 64. Bore 63 is opened at its righthand end as viewed in the drawing to permit adjustment of the set screw to vary within precise limits the final position of finger 68 at the end of a feed stroke. Slide member 78 has a bushing 78a on each end thereof to give it a sliding fit within bore 63. A pin 82 extends from the slide member laterally through an elongated slot 83 in the side of block 60 and this pin in turn is pivotally connected to one end of a lever 84. This lever has a sliding pivotal connection intermediate its ends in the slotted head 86 of a pin having a stem portion 87 which is rotatably received within an axial bore in a bolt 88. This bolt is adjustably locked by means of a nut 90 in a guide track 92 provided in a bracket 94 which is secured by bolts 96 to one leg of the press frame. As explained more fully below, bolt 88 can be positioned at any desirable point on guide track 92 thereby to permit an infinite adjustment within guide track limits of the stroke of the feed plunger for varying sizes of terminals.

The opposite end of lever 84 is pivoted at 98 to a link 100 which in turn is pivotally connected at 102 to a slide member 104 which is horizontally reciprocable in the embodiment shown in guide ways 105 provided between the legs of the press frame 2. In the section of this slide member which lies behind press ram 28, there is provided a cam track 106 which receives a cam follower 108 mounted on the press ram so that as the ram

is raised from the position of Figure 4, slide member 104 moves to the left in this figure while during descend of the ram, slide member 104 moves to the right. A straight section in cam track 106 at its lower end provides a dwell of the feed mechanism during the crimping part of the ram travel. The remainder of the cam track provides uniform acceleration and deceleration of the feed mechanism throughout its entire travel.

It is advantageous to provide a means for applying a light downward pressure on the strip of terminals so that the strip will be held against accidental movement other than the feeding motion. In the disclosed embodiment a holdown means is provided in the form of a generally U-shaped bracket 110 having portions which extend across the top of block 41 and which bridge the space between the guideways 56. This U-shaped bracket has a section which extends downwardly along the side of block 42 and beneath and into a recess on the underside of the block. A spring 112 bears against this foot portion of the bracket and normally biases the entire bracket downwardly thus to apply a light pressure against the terminal strip. In order to permit raising of this hold-down device as when a new strip of terminals is threaded through the mechanism, an extension 114 is provided which projects upwardly through a slot in bracket 62 and has mounted on its end a cam 116 so that as this cam is rotated in a clockwise direction as viewed in Figure 4 the hold-down bracket is pulled upwardly against the force of spring 112.

In operation, and assuming the parts are in the position of Figure 1 with the ram at its top dead center position, upon downward movement of the ram, slide member 104 is moved rightwardly from the position of Figure 1 to the position of Figure 4. This causes lever 84 to be oscillated in a clockwise direction about its pivot point in the head of pin 86. During such oscillation, slide 78 moves leftwardly as viewed in Figure 4 and pushes plunger 64 to the position shown in Figure 4 to feed the first or leading terminal in the strip to a position beneath the crimping dies. Thereafter the ram continues to descend and upon its reaching its bottom dead center position the terminal is crimped onto a wire. It will be apparent upon reflection that as lever 84 oscillates in a clockwise direction, its motion with respect to pin 86, 87 is not a simple pivoting on the axis of pin 87 but must also include some sliding of the lever in the slotted head of the pin. This sliding motion of lever 84 takes place by reason of the fact that the motion of slide 78 is rectilinear rather than arcuate, therefore, the pivotal axis of the lever 84 must undergo continuous change during the oscillation.

On upward movement of the ram, the motions described above are followed in reverse order, that is slide 78 is retracted as lever 84 oscillates in a counterclockwise direction around its pivotal axis and link 100 and slide member 104 move leftwardly as viewed in Figure 4. Plunger 64 is retracted during this upward movement of the ram by virtue of spring 74 which pulls the plunger rightwardly so that it is positioned at the end of the up stroke of the ram behind the next adjacent terminal in the strip.

The disclosed arrangement for feeding terminals to the crimping press provides substantial advantages over previously available systems for performing this operation. It will be noted that an infinite degree of adjustability is permitted for the stroke of the feed finger by virtue of the sliding arrangement for the pivotal axis for lever 84. Moreover, such adjustment of the stroke can be made rapidly by reason of the fact that the nut 88 need merely be loosened and positioned properly on track 92 to achieve the proper stroke. Since track 92 is parallel to lever 84 when the lever is oscillated to the limit of its clockwise travel (as shown in Figure 4), adjustment of the position of nut 88 does not change the position of feed finger 68 when this finger is at the end

of its leftward travel. In other words, when the stroke is shortened or lengthened by adjustment of nut 88, the limit of the return stroke is changed and not the limit of the forward (feeding) stroke. This arrangement is advantageous in that, when the apparatus is adjusted for a shorter terminal, it is necessary to adjust nut 88 but it is not necessary to adjust the position of setscrew 80. Adjustments can be made for the final positioning of the feed finger by means of set screw 80 when necessary. These features of adjustability are of importance in any press where varying types of terminals are used because of the fact that the feed stroke for any given terminal must be precisely controlled and the positioning of the terminal at the end of the feed stroke must be accurately fixed for proper crimping.

In the disclosed arrangement with the shape of the cam track 106 as shown, and taking into consideration the motion of the ram 28, a feeding stroke is achieved in which the finger first accelerates at a constant rate to a maximum velocity and then decelerates at a constant rate until it comes to a halt and dwells during a brief interval during which the terminal is crimped. Such constant acceleration and deceleration of the feed finger is highly desirable, particularly where, as in many crimping presses, feeding takes place within an extremely short time interval, since the terminal being fed comes to a halt slowly and its inertia at the end of the feeding stroke is extremely low. By reason of this fact, there is little or no tendency for the terminal to be misaligned or improperly positioned with respect to the crimping dies. On the other hand where the terminals are fed in a stroke that involves a nonconstant deceleration, as with many prior art feeding devices, the terminals have a substantial amount of inertia at the end of the stroke and this inertia is damped out when the terminals come to a stop. At that time, there is a tendency for the terminals to vibrate and become misaligned with respect to the crimping dies.

By reason of the constant acceleration and constant deceleration rates achieved with the instant device, the component parts of the feeding mechanism can be relatively light in weight and this feature is desirable because of the fact that terminals frequently are made from relatively light gauge material and it is not desirable to impose heavy stresses on them by the feed finger or the hold-down device. For example, in the instant apparatus, the hold-down device 110 can be arranged such as to impose only a very light downward force on the strip of terminals whereas in previous feeding mechanisms it was often necessary to impose a substantial downward force in order to prevent overfeeding.

It will be noted that the feed finger 68 moves along a rectilinear path and during the actual feeding strokes it does not rotate about its pivot point on ear 66. In many prior art feeding devices, on the other hand the feeding finger has been pivotally mounted on a pivot point which follows an arcuate path during the feeding stroke. The disclosed arrangement is preferable in that the terminal being fed is not subjected to unbalanced and changing forces as it is pushed toward the crimping zone. Such unbalanced and changing forces on the terminal sometimes have a tendency to misalign the terminal with respect to the crimping dies, particularly, where the terminals are relatively small and are of thin gauge material.

The instant device feeding mechanism feeds the terminal on the down stroke of the ram and delivers the terminal to the feeding zone before the crimping dies arrive at their bottom dead center position. This arrangement is very desirable in fully automatic lead-making machines since the alternative of feeding the terminal on the upstroke of the ram requires that the feed finger moves over the strip of terminals during the down stroke in order to be in position for the next feeding cycle. This movement of the finger relative to the terminals after the completion of feeding may cause

misalignment of the terminal. Where it is necessary to feed the terminal on the up stroke (as in the semiautomatic lead making machines), it is only necessary to change the direction of the upper portion of cam track 106 thereby to cause slide member 104 to move leftwardly on the down stroke and rightwardly on the up stroke of the ram.

As an alternative to having the set screw 80 abut plunger 64, it is feasible to have the slide members 78 and plunger 64 intergrally connected to each other by means of an adjustable set screw having right and lefthanded threads thereon. Where this arrangement is employed rather than the disclosed arrangement the spring 74 can be eliminated if desired and adjustment of the position of the feed finger is achieved by rotation of the right and lefthanded screw so that the parts move towards or away from each other as the screw is turned.

I claim:

1. Apparatus for feeding terminals comprising, a ram reciprocable towards and away from a crimping zone, a terminal feed track extending towards said zone, reciprocable feed means for pushing a terminal along said track towards said zone, a lever pivotally connected at one end to said reciprocable feed means, said lever being pivotally mounted intermediate its ends and being slidable relative to its intermediate pivotal mounting, a slide reciprocable along a path extending adjacent to, and transversely of the direction of reciprocation of, said ram, cam means acting between said slide and said ram for moving said slide in a first direction during descent of said ram and in the opposite direction during ascent of said ram, and a link connecting said slide to the opposite end of said lever thereby to oscillate said lever and actuate said feed means, said pivotal mounting being adjustable along a locus extending parallel to said lever when said feed means is in its forward position thereby to permit changing of the amplitude of the feed stroke without changing the forward limit of the feed stroke.

2. Apparatus for feeding and crimping terminals comprising, a ram reciprocable towards and away from a crimping zone, a terminal feed track extending towards said zone, a terminal feed slide member reciprocable along a confined rectilinear path towards and away from said zone, means reciprocated by said terminal feed slide member for pushing a terminal along said terminal feed track towards said zone, a lever pivotally connected at one end to said terminal feed slide member, a pivotal mounting for said lever, said lever being longitudinally slidable relative to said pivotal mounting while being pivotally oscillated thereon, an actuating slide member reciprocable along a path extending substantially normally of the path of reciprocation of said ram, cam means acting between said ram and said actuating slide member, and a link connecting said actuating slide member to said lever whereby, upon reciprocation of said ram, said lever is oscillated and slides relative to said pivotal mounting, and said terminal feed slide member is reciprocated along said confined path thereby to feed a terminal towards said crimping zone.

3. Apparatus for feeding and crimping terminals comprising a ram reciprocable towards and away from a crimping zone, a terminal feed track extending towards said zone, a terminal feed slide member reciprocable along a confined rectilinear path towards and away from said zone, a feed plunger reciprocable along said confined path and disposed adjacent said terminal feed slide member, means on said plunger for engaging and feeding terminals, resilient means normally biasing said plunger against said terminal feed slide whereby, upon reciprocation of said terminal feed slide, a terminal is fed towards said crimping zone by said feed plunger, a lever pivotally connected to said terminal feed slide, a pivotal mounting for said lever, said lever being longitudinally slidable relative to said pivotal mounting while being pivotally oscillated thereon, and motion transmitting means for

transmitting motion from said ram to said lever thereby to oscillate said lever and to reciprocate said terminal feed slide member.

4. Apparatus for feeding and crimping terminals comprising, a ram reciprocable towards and away from a crimping zone, a feed track extending towards said zone, a plunger movable along a confined path towards and away from said zone, means on said plunger for pushing a terminal along said track towards said zone, a feed slide disposed adjacent said plunger and reciprocable along said confined path, resilient means normally biasing said plunger against said feed slide, and means for reciprocating said feed slide along said confined path thereby to reciprocate said plunger and to feed a terminal along said track.

5. Apparatus as set forth in claim 4 including extendible means interposed between said feed slide and said plunger to permit adjustment of said slide and said plunger towards and away from each other.

6. Apparatus for feeding and crimping terminals comprising, a ram reciprocable towards and away from a crimping zone, a terminal feed track extending towards said zone, a feed plunger movable along a confined path towards and away from said zone, means on said plunger for pushing a strip of terminals along said terminal feed track towards said zone upon movement of said plunger towards said zone, resilient means normally urging said plunger in a direction away from said zone, a slide member disposed on said confined path, and motion transmitting means extending between said slide member and said ram for reciprocating said slide member along said

10

20

25

30

confined path whereby said plunger is reciprocated and a terminal is fed toward said crimping zone.

7. Apparatus for feeding terminals comprising, a ram reciprocable towards and away from a crimping zone, a terminal feed track extending towards said zone, reciprocable feed means for pushing a terminal along said track towards said zone, a lever pivotally connected at one end to said reciprocable feed means, said lever being pivotally mounted intermediate its ends and being slideable relative to its intermediate pivotal mounting, and motion transmitting means between the opposite end of said lever and said ram for oscillating said lever whereby, upon reciprocation of said ram, said feed means is reciprocated and a terminal is fed into said crimping zone, said pivotal mounting for said lever being adjustable along a locus extending parallel to said lever when said feed means is in its forward position thereby to permit changing of the amplitude of the feed stroke without changing the forward limit of the feed stroke.
